UNITED STATES PATENT OFFICE.

GEORGE F. SLIPP, OF LOWELL, MASSACHUSETTS, ASSIGNOR TO SACO-LOWELL SHOPS,
OF BOSTON, MASSACHUSETTS, A CORPORATION OF MASSACHUSETTS.

YARN-SIZING MACHINE AND METHOD OF OPERATION THEREOF.

Application filed May 22, 1922. Serial No. 562,629.

To all whom it may concern:

Be it known that I, GEORGE F. SLIPP, a citizen of the Dominion of Canada, residing at Lowell, in the county of Middlesex and 5 Commonwealth of Massachusetts, have invented new and useful Improvements in Yarn-Sizing Machines and Methods of Operation Thereof, of which the following is a specification.

10 This invention relates to improvements in so-called slashers or machines for sizing warp yarns, and to methods of operating the same during the tying in of the yarn ends, and its object is to allow the saving 15 of large quantities of yarn which under prevailing practice have to be thrown away each time a new "set" of yarns is inserted in the machine.

The invention relates particularly to 20 mechanism incorporated in such machines, whereby it is made possible to continue to rotate the size rolls in the sizing vat or tank, while the rest of the machine is not in operation.

25 In the machines of the character referred to, when a new set of warp yarns is to be introduced into the machine, the machine is stopped for the considerable period necessary to enable the operator to "count in" 30 the new "ends", and in such machines, as now in use, the size rolls, which constitute one element of the machine and which are partially immersed in the sizing material, are stopped with the other parts of the 35 mechanism, with the result that a scum forms on the surface of the sizing in the tank and the sizing, moreover, becomes hardened on the size rolls, particularly along lines at the top level of the sizing, and then when 40 the machine is started up, this hardened sizing, coming in contact with the yarn, gums the yarns together causing trouble as the 45 yarns pass through the comb. If this is to be avoided, the rolls must be cleaned off to remove the hardened size, and the scum, moreover, has to be removed from the top of the sizing in the vat.

When, therefore, with machines as at 50 present organized, a new set of "ends" is to be counted in, which operation must be performed at the front end of the machine, it is inevitable that there will be a defective portion in the yarn at a distance from the

front end of the new set about equal to the distance of travel of the yarn from the size 55 rolls to the delivery roll, which is usually a matter of 25 or 30 yards, unless the size rolls are cleaned off after the new set is counted in and before the machine is started again. Accordingly, it is the customary 60 practice at the present time, at least in pattern work and sometimes in plain work, not to attempt to size these first 25 or 30 yards of the new set at all, but to cut them off and discard them as waste, rather than to 65 take the time to clean off the size rolls. Moreover, in any case, the scum must be removed from the sizing in the tank.

By the use of my invention all but a small 70 part of this heretofore wasted yarn is saved, and the formation of a scum on the sizing is avoided.

In the accompanying drawings,

Figure 1 is a diagrammatic side elevation of a slasher or sizing machine, with parts of 75 the mechanism hereinafter referred to omitted for the sake of clearness;

Fig. 2 is an elevation showing in part the clutch mechanism hereinafter referred to, 80 looked at from the side of the machine; and

Fig. 3 is a sectional view of said clutch mechanism, on the line 3-3 of Fig. 2.

Referring to Figure 1,—1, 1, 1, indicate 85 yarn beams from which yarn as indicated at *a* passes to a sizing tank 2, mounted in a suitable frame-work 3, and filled with sizing, as usual, to a level high enough to submerge the lower portions of the size rolls 4, 4^a. The yarn passes from the yarn beams over the guide rolls 5, 5; thence into the sizing under the immersion roll 6; thence between the first size roll 4 and the co-operating upper squeeze roll 7; thence between the second size roll 4^a and the co-operating upper squeeze roll 7^a; thence over and around the drying cylinders 8 and 9 and to the driven delivery roll 10, as indicated in Figure 1, the delivery roll 10 co-operating with rollers 11 and 12 to draw the yarn through the machine. From the delivery roll the 90 yarn passes to the loom beam 13, upon which it is wound as it leaves the machine.

100 The size rolls are driven in usual manner, that is to say, by means of a shaft 14, known as the side-shaft, running along the 105 side of the machine, which carries a bevel

gear 14^a, which bevel gear drives, by well known intermediate gearing, the shafts of the two size rolls.

The mechanism thus far described is common to slashers now in use and requires no detailed description.

In machines of this class as heretofore in use, the shaft through which power is transmitted to the size rolls has been so connected

10 up with the mechanism for driving the delivery roll that the delivery roll is rotated at all times when the size rolls rotate, so that it is impossible to stop the progress of the yarn through the machine without also 15 stopping the rotation of the size rolls.

I have provided mechanism whereby the delivery roll of the machine may be stopped without stopping the rotation of the size rolls this mechanism being shown in detail 20 in Figs. 2 and 3.

Referring to these figures, 15 is a shaft mounted in suitable bearings, one of which is indicated at 16, which carries the delivery roll 10. Upon an extension 15^a of this shaft 25 is mounted the centrally bored gear member 17, which is free to rotate on the shaft 15^a and which carries the two gears 18 and 19, these two gears, therefore, always rotating in unison. A collar 17^a provided on shaft 30 15^a holds the member 17 in proper position longitudinally of the shaft.

Power for driving the machine is transmitted to the mechanism through the gear 18, which meshes with a suitable driving 35 gear, not shown. Gear 19 meshes with a bevel gear 20, mounted on the front end of the shaft 14. Rotation of gear 18, therefore, causes the rotation of said shaft 14, and thereby of the size rolls 4 and 4^a, through 40 the intermediate gearing heretofore mentioned.

21 is a clutch member which as shown consists of an inner sleeve 22 and an outer sleeve 23, rigidly connected therewith in 45 any suitable manner, the clutch member being mounted on the extension 15^a of the shaft 15 and being keyed thereto by means of the key 24, so that rotation of the clutch member will cause the rotation of the shaft 50 15^a, 15, the clutch member being, however, movable longitudinally on said shaft.

At the inner end of the clutch member are clutch teeth 25 adapted to engage with clutch teeth 26 carried by the gear 18 when 55 the parts are in the position indicated in Fig. 3, so that when the parts are in this position rotation of the gear 18 causes the rotation not only of the size rolls but also of the delivery roll 10. 27 is a lever for controlling the clutch, which is pivoted at 28^a

upon a bracket attached to the frame of the machine, 28, and carries at its end a fork 29, which engages in a peripheral groove 30 in the clutch member by means of pins 31 carried by the fork. By moving this lever, 65 therefore, the clutch member may be moved out of engagement with the gear 18, and thereby the delivery roll may be stopped without stopping the size rolls.

The lever is provided with a latch 32 of 70 well-known form for locking the lever, so as to hold the clutch either in operative or in inoperative position.

The mechanism above described enables me to continue the rotation of the size rolls 75 of the machine during the time when the delivery roll is stopped, so that the yarn is not being fed through the machine; and by keeping the size rolls constantly rotating during the periods when the machine is shut 80 down, I prevent any deposit of hardened sizing upon the size rolls and prevent the formation of any scum on the surface of the sizing.

With a machine equipped with the mechanism above described, when a new set of "ends" is to be tied in, the clutch is disconnected so as to stop the delivery roll and the upper squeeze rolls 7 and 7^a and the immersion roll 6, are raised in usual manner. Then 90 when the machine is to be started again, these rolls are replaced and the clutch moved into engaging position so as to start the delivery roll.

What I claim as new and desire to secure 95 by Letters Patent is:—

1. In a yarn sizing machine, a sizing tank, size rolls therein, a delivery roll, a delivery roll shaft, a gear member mounted loosely on an extension of said shaft and operatively connected with the size rolls, a clutch member keyed to said shaft and movable longitudinally thereon, and means for engaging and disengaging said clutch member with said gear member. 100 105

2. The method of operation during the tying-in of the ends in a yarn-sizing machine which consists in stopping the passage of the yarn through the machine by stopping the delivery roll and removing the upper 110 squeeze rolls from the size tank, and continuing the rotation of the size rolls in the size tank.

3. The method according to claim 2 in which the immersion roll and the yarn are 115 removed from the size tank.

In witness whereof I have signed my name to this specification.

GEORGE F. SLIPP,
